UNITED STATES PATENT OFFICE.

EDWARD CARRAU, OF CATHLAMET, WASHINGTON, ASSIGNOR OF ONE-HALF TO
PACIFIC CADEAU, OF CATHLAMET, WASHINGTON.

RAILWAY-BRAKE MECHANISM.

1,119,242.

Specification of Letters Patent.

Patented Dec. 1, 1914.

Application filed February 3, 1913. Serial No. 746,032.

To all whom it may concern:

Be it known that I, EDWARD CARRAU, a citizen of the United States, residing at Cathlamet, in the county of Wahkiakum 5 and State of Washington, have invented certain new and useful Improvements in Railway-Brake Mechanism, of which the following is a specification.

This invention has relation to a rail-road 10 train, and refers more particularly to improved means for quickly stopping such train.

The object of my invention, in a broad sense, is to provide means on the locomotive 15 or cars of a train for engaging the rails on which said locomotive and cars travel, for the purpose of stopping the train.

A further object is the provision of means for operating the device from the air system usually employed on rail-road trains.

The further objects and advantageous features of my invention are hereinafter fully described, and drawings are embodied for the purpose of facilitating the perusal of 25 said description, and in order to enable those versed in the art to readily construct the device.

In the drawings: Figure 1 illustrates, in front elevation, my device in its relation to 30 a rail-road track, Fig. 2 is a side elevation of a wheel-truck embodying my invention, and Fig. 3 shows a modification of my invention which will be more fully herein-after explained.

My invention readily adapts itself for use on any wheel-truck. I show for the sake of simplifying this description a mere outline of a wheel-truck having a transverse member 1, on which an air-cylinder 2 is pend- 35 ently fixed by suitable bolts 3. The piston of said cylinder is rigid on a pendent rod 4, which at the bottom terminates in a bifurcated head 5. Equidistantly spaced on each side of the cylinder the cross-member 1 car- 40 ries pendent rods 6, 7, said rods having at the bottom bifurcated heads 8 in which a pair of levers 9 are pivotally hung. The inner ends of said levers journaled on a pin 10 of the bifurcated head 5. A pair of 45 pendent studs 11 are fixed in the cross member 1, and said studs carry heads 12 having bifurcations disposed at right angles to the aforesigned bifurcations. Bolts 13 are fixed in said stud-heads, and a pair of pendent 50 jaws 14, 15 are held suspended from each

of said bolts in vertical alinement with the rails 16, 17 of the car-track. The outer ends of the levers 9 are made with elongated perforations within which said jaws are held confined, and said jaws have lateral projections 18, 19 for engagement with the levers. The said jaws are free to slide vertically on the studs 13 by elongating the perforations through which said bolts extend. A stiff spring 20 is mounted on the piston rod 4 for 60 the purpose of depressing the inner ends of the levers 9, whereby the outer ends of the latter are caused to rise and in turn to raise the jaws to the position shown in full outline in the drawing. The jaws are 65 yieldingly held separated by interposed springs 21.

The mechanism thus far described holds the jaws elevated and inoperative. It is noticed that a tube 22 extends from the bottom of the air-cylinder 2 to the usual air-tank 23. A valve 24 is cut into said tube, and said valve is by a rod 25 operatively connected with a hand-lever 26 positioned above the car-platform. The operator turns 70 said hand-lever, thereby opening the valve, which operation causes air to rush into the cylinder 2 and to raise the piston and piston rod. This in turn causes the levers 9 to tilt, during which movement their outer ends 75 swing downward followed by the jaws 14, 15, which latter drop until checked by their fulcrum-bolts 13. It is noticed that the said jaws gradually widen toward the bottom, and as they are confined within the ends of 80 the levers 9, they are, during the continued movement of the latter, caused to gradually close. The inner surfaces of the opposed jaws 14, 15 are made with recesses 27, 28 shaped to correspond with the contour of 85 the rails 16, 17. The jaws, in closing, encompass the crown of the said rails, and bring the train to a quick stop. This condition is shown in dotted outline in Fig. 1.

The valve 24 is made with an exhaust vent 100 for the air in the cylinder 2, and so related that the closing of said valve causes said vent to open, whereupon the spring 20 quickly returns the mechanism to its initial position. This valve construction is well 105 known, and commonly used, no further explanation is therefore thought necessary.

In Fig. 3 is shown a jaw mechanism which varies from the above in the manner of operating the jaws. The jaws 30, 31 are op- 110

ferred to close in the manner described, and are made on their opposed inner faces with recesses 32, 33 adapted to receive a rib 35 of the operating lever 34. As the latter tends to close the jaws the said member slides in the opening formed by said recesses, as shown in dotted outline, and as the lever 34 again rises, the said wedge-shaped member rides along the inclined surfaces 36 of said recesses, thereby positively forcing the jaws apart.

From the above description it is seen that compressed air is used to set the brake, and a spring mechanism is provided for releasing the brake.

My invention may be constructed of any material and made any size deemed suitable for all the requirements of such a device, and while I have illustrated and described a preferred form of construction and combinations of elements considered essential in characterizing the same, I wish to include in this application all mechanical equivalents and substitutes that may be fairly considered to come within the scope and purview of my invention as defined in the appended claims.

I claim—

In a device of the character described, the

combination with a railway-car, of a transverse beam, bifurcated heads suspended from the beam, pivotally mounted jaws depending from said heads, lateral projections integral with said jaws, recesses in said jaws to conform with the contour of the heads of railway-tracks, pendent rods supported by the beam, a cylinder attached to the beam, a piston operable in said cylinder, a rod fixed at one end to said piston, a bifurcated head attached to the free end of said rod, a collar attached to said piston-rod intermediate the bifurcated head and cylinder-head, a spring encircling said piston-rod intermediate the collar and cylinder-head, connecting means from the cylinder to an air supply, levers pivoted to the head of the piston-rod and pendent rods, said levers being adapted to engage the lateral projections of the jaws and operate said jaws vertically, and means to space apart said jaws, substantially as set forth.

In testimony whereof I have hereunto affixed my signature.

EDWARD CARRAU.

In presence of—

D. HUMMER,

DAVID E. LOFGREN.
